Primary Examiner — Brett Miller*Assistant Examiner* — Rani J Abdallah(74) *Attorney, Agent, or Firm* — The Morales Law Firm; Joseph L. Morales, Esq.(57) **CLAIM**

What is claimed, is an ornamental design for a bottle, as shown and described.

DESCRIPTION

FIG. 1 is a perspective view of a bottle;

FIG. 2 is a front view thereof;

FIG. 3 is a side view thereof;

FIG. 4 is a top view thereof; and,

FIG. 5 is a bottom view thereof.

The broken lines shown illustrate portions of the bottle that form no part of the claimed design.

1 Claim, 5 Drawing Sheets(56)
